Primary Examiner — Darlington Ly(57) **CLAIM**

The ornamental design for a pen, as shown and described.

DESCRIPTION

1. Pen

1.1 is a top and side perspective view of a pen showing my new design;**1.2** is a front elevation view thereof;**1.3** is a side elevation view thereof;**1.4** is a top plan view thereof, the bottom plan view being a mirror image;**1.5** is a partially exploded side elevation view thereof with the cap removed;**1.6** is a fully exploded top and front perspective view thereof;**1.7** is a perspective view thereof wherein the pen is shown configured with other pens into a pyramid structure;**1.8** is a perspective view thereof wherein the pen is shown configured with other pens and objects; and**1.9** is a perspective view thereof wherein the pen is shown configured with other pens into a cube structure.

The broken lines in the drawings illustrate portions of the pen and environmental subject matter of additional pens, paperclips, and a ruler that do not form part of the claimed design.
